United States Patent Office.

CHARLES POWELL, OF BIRMINGHAM, ENGLAND.

Letters Patent No. 94,027, dated August 24, 1869.

IMPROVEMENT IN PUMPS.

The Schedule referred to in these Letters Patent and making part of the same.

To all whom it may concern:

Be it known that I, CHARLES POWELL, of Birmingham, England, have invented a new and useful Improvement in Pumps; and I do hereby declare that the following is a full, clear, and exact description thereof, which will enable those skilled in the art to make and use the same, reference being had to the accompanying drawings, forming a part of this specification.

This invention relates to certain new and useful improvements in pumps.

The invention consists in a novel construction and arrangement of parts hereinafter described, to wit, the form of the upper part of the pump-barrel, the application of air-chambers, and a self-acting tap or leak, whereby a much more desirable pump than usual for general purposes is obtained.

In the accompanying sheet of drawings—

Figure 1 is a side view of my invention.

Figure 2, a vertical section of the same.

Similar letters of reference indicate corresponding parts.

Figure 1 represents a wooden pump-stock, A, with a portion thereof cut away so as to leave it nearly in the form of a chair.

On the seat of said chair-stock is placed an air-chamber, B, whose edges, b, fit into corresponding recesses on the stock.

The bore of the pump-stock terminates at the top in the inverted frustum of a cone.

The air-chamber is provided with a central tube, c, which extends down within a bore, a, and terminates a short distance above the eduction-pipe C, said tube c being braced by cross-pieces d.

The air-chamber B is secured to the chair-shaped back, D, of the pump, by means of screws passing through ears or lugs e, on the air-chamber, into the back.

The upper part of the pump is reduced to about one-third of its thickness, by removing two-thirds, giving to the part of the pump above the platform of the well something of the shape of a chair.

The portion of the air-chamber above the bore may be made of various forms; it may be swelled out, or made smaller in diameter, perfectly cylindrical, or flat at one or more sides, so that such side or sides will be in line with the ears or lugs e.

The top of the air-chamber is provided with a stuffing-box, F, through which the piston-rod F passes.

The gland of this stuffing-box may be tightened by screw-bolts, or it may be provided with a screw-thread to work in a female thread in the interior of the upper part of tube c.

The piston-rod passes through the tube c, and the portion of said rod which works in c, may be of steel, to obtain lightness with a requisite degree of strength.

G is an air-chamber, connected to the eduction-pipe C.

This air-chamber is of cylindrical, balloon, or other suitable shape, and it may be cast in one piece with C, or cast separately, and attached to it in any proper way.

In cases where the air-chamber G alone is used, I place a stuffing-box, of any proper kind, in the top of the bore a of the pump-barrel.

The pipe C is screwed in or on to the barrel A, and it is provided with a flange, d, to abut against A. (See fig. 2.)

J represents a curved or bent tube, which is screwed into the barrel A of the pump under the platform of the well, and at a sufficiently low point to be beyond the action of the frost.

In a force-pump, the horizontal part of this tube is supplied with a ball or other valve, J*, (see fig. 2;) said valve closing the orifice when the force is applied, and opening of itself when the pump is not in operation; the ball-valve being of sufficient weight to yield, only to a strong pressure from the pump-cylinder.

The outlet of the tube J is provided with a stopper, j, attached to a rod, K, which extends upward through the platform of the well, the stopper having a tendency to close the outlet of tube J, by virtue of its own weight, or with the aid of a spring, or other means.

The rod K is also provided with a lid, k, which is directly over the mouth of a vessel, L, containing water, or other substance capable of freezing, and which, in freezing, will raise the lid k and rod K, and thereby lift the stopper j, and admit of the water within the pump escaping before it has time to freeze.

The vessel L may be made of various shapes, but an inverted frustum of a cone would probably be as desirable a form as any.

The vessel L communicates with the interior of the pump by a horizontally-projecting tube, l, containing a ball or other valve, m, when the device is applied to a force-pump.

I claim as new, and desire to secure by Letters Patent—

1. The combination of the tube J, rod K, having stopper j, and lid k, thereon, tube l, and hollow stock A, all being connected and constructed as set forth, to cause the escape of water within the pump before it can freeze, in the manner described.

2. The combination of the chair-shaped wooden stock, A, with air-chamber B and piston F, as and for the purpose specified.

3. The improved pump, the same consisting of the devices named and described.

CHARLES POWELL.
